UNITED STATES PATENT OFFICE.

JOHN C. BELL, OF CLEVELAND, OHIO.

BILL.

971,106.

Specification of Letters Patent. Patented Sept. 27, 1910.

Application filed July 29, 1908. Serial No. 445,917.

To all whom it may concern:

Be it known that I, JOHN C. BELL, of Cleveland, in the county of Cuyahoga and State of Ohio, have invented certain new and 5 useful Improvements in Bills; and I do hereby declare the following to be a full, clear, and exact description of the invention, such as will enable others skilled in the art to which it appertains to make and use the 10 same.

This invention relates to improvements in bills and more particularly to such as are adaptable for use by gas companies or other concerns furnishing light or power to their 15 customers, in rendering statements of account.

The object of my invention is to provide a bill which shall be so constructed that it can be rendered by the employee of the company 20 when he takes the state of the meter and so that it will be impossible for the customer to alter the amount of the bill without the knowledge of the company.

A further object is to so construct and 25 arrange a bill of the character described that it can be prepared with a minimum amount of writing and so that it can be received and stubs furnished for the use of the company in posting its books, in a minimum 30 amount of time.

With these objects in view the invention consists in certain novel features of construction as hereinafter set forth and pointed out in the claims.

35 The accompanying drawing is a view of a gas bill embodying my improvements and having indicated thereon lines on which the parts of the bill may be severed.

1 represents a gas bill having, at an intermediate part thereof, the designation of the 40 company's name. In this intermediate portion of the bill is printed in two lines words relating to a former reading of a meter and to the reading of the meter at the time the 45 bill is rendered. In the case of a gas bill these designations will relate to cubic feet and will be filled out in accordance with the readings of the meter at the two periods mentioned. Below the above designations 50 of meter readings is another designation of cubic feet which, when filled out will indicate the difference between said meter readings and therefore state the number of cubic feet of gas which has been consumed during 55 the period for which the bill is rendered. In this lower line of designations may also be

indicated the price of gas,—such for instance as \$1.10 per one thousand cubic feet. Below the designations above described a space 2 is left in which the name and address of 60 the consumer are written and in this space may also be indicated the ledger and page in which the particular account is kept.

At the extreme left of the bill a portion 3 is provided and forms when severed part of 65 an auditor's coupon or stub, and at the extreme right of the bill a cashier's stub 4 is provided and arranged with a space to receive the date on which the bill may be discounted as designated by the context and 70 also designed to receive data indicating the ledger and page thereof where the account may be found.

At the left of the body portion 1 of the bill four, more or less, blocks of figures are 75 printed alternately in different colors. The block 5 of figures (printed in red) comprises two columns. The column 6 of this block comprises figures or designations of amounts of money counting from 11 cents 80 at the bottom to \$3.30 at the top and indicating the gross amount of the bill, in accordance with the number of cubic feet of gas consumed which is indicated by the figures in column 7. Thus if 3,000 feet of gas 85 be consumed, the gross price at \$1.10 per thousand will be \$3.30 as indicated at the top of column 6. The next block 8 of figures (printed in black) comprises four columns, 90 *a, b, c, d*, the columns *a, b*, having the same designations and significance as the columns of figures 6—7 of the block 5, except that said columns *a, b*, of block 8 are arranged in reverse order to the columns of block 5, so that the column 7 of block 5 in which 95 "cubic feet" are indicated and the column *b* of block 8 in which "cubic feet" are indicated will be adjacent to each other. The figures of the column *c* of block 8 indicate the amounts of discount if the bill is paid 100 within a specified time, and the figures of column *d* represent the amounts of a bill when the same has been discounted. Thus, if 3,000 cubic feet of gas has been consumed, the amount of discount will be 30 cents, as 105 indicated at the top of column *c*, and the amount of the discounted bill will be \$3.00, as indicated at the top of column *d*. The block of figures 11 is printed in red and the columns of this block constitute continuations of the columns of block 5. Similarly 110 the block of columns 12 which is printed in

black, constitutes a continuation of the block of columns 8.

At the right of the body portion 1 of the bill four blocks of columns of figures and 5 designations 13, 14, 15 and 16 are printed and are duplicates of the blocks of columns and designations 5, 8, 11 and 12, above described.

Let it be assumed that the gas company 10 is to issue a bill to John Doe and that the former reading of his meter was 70,100 cubic feet. The clerk at the gas office will write the customer's name and address on the bill and also indicate that the former 15 reading of the meter was 70,100 cubic feet. This bill will be taken to the premises of the customer and it is found that the present or last reading of the meter is 74,000 cubic feet. The company's employee finds 20 that the difference between these two readings is 3,900 cubic feet which indicates the amount of gas consumed. The company's employee will now sever the bill, with the use of a suitable instrument, on the line 25 $x-x$ and retain the auditor's coupon thus formed. The bill which is left with the consumer will indicate by the figures 3.9 in the first column of block 12 that 3,900 cubic feet of gas has been consumed; that the 30 gross cost of the gas consumed is \$4.29, as indicated in the next column of block 12; that the amount of discount is 39 cents, as shown by the next column of block 12, and that the net amount of the bill, if the latter 35 is paid on or before the date indicated on the stub at the right hand end of the bill, is \$3.90, as shown in the column of block 12 next to the body portion of the bill. The number of cubic feet of gas consumed and 40 the gross amount of the bill are given to the auditor by the figures appearing in the columns of block 11 reading horizontally immediately above the point of severance on the line $x-x$. If the bill be paid on or before the last discount day, the amount of the 45 bill would be \$3.90 and the clerk at the gas office would sever the bill on the line $y-y$, retain the stub 4 thus formed and deliver the

remainder of the bill to the customer so as to constitute a receipt for him. The coupon 50 4 containing a portion of the block 16 will indicate to the cashier the data of the bill which has been paid.

Having fully described my invention what I claim as new and desire to secure by Letters Patent, is,—

1. A bill of the character described, comprising a body portion suitably designated to indicate the name of a customer, said bill having at each side of its body portion, two 60 blocks of figures, the figures of one column of each block suitably designated to indicate the amount of fluid consumed and another column of each block suitably designated to indicate the charge for the fluid 65 consumed, said bill suitably designated at one end to form an auditor's stub and said bill suitably designated at the other end to form a cashier's stub severable with portions of said blocks of figures, and the remaining 70 portions of said columns of figures forming parts of the body of the bill.

2. A bill of the character described, comprising a body portion suitably designated to indicate the name of a customer and also 75 designated to contain meter readings, said bill provided at its respective ends with stubs suitably designated as auditor's and cashier's stubs, said bill having at each side of the body portion and between the latter 80 and said stub portions, a plurality of blocks of figures arranged in columns, the figures of the columns of certain of said blocks suitably designated to indicate successively, "feet," "gross," amount of bill, amount of 85 "discount" and "net" amount of bill, and the figures of the columns of the other blocks suitably designated to indicate "feet" and the "gross" amount of the bill.

In testimony whereof, I have signed this 90 specification in the presence of two subscribing witnesses.

JOHN C. BELL.
